UNITED STATES PATENT OFFICE

JOHN MURRAY, OF CHOBHAM, ENGLAND

DEVICE FOR AUTOMATICALLY FEEDING BOOKCASES TO BLOCKING PRESSES

Application filed July 1, 1929, Serial No. 375,311, and in Great Britain July 2, 1928.

This invention relates to devices for automatically feeding book cases or book covers to a blocking press or the like and has for its object to provide improved means for effecting positive registration of the case in relation to the impressing surfaces of the machine.

In the feeding mechanism hitherto employed the case was brought into register by laying the outside edges of the case to guides. This mode of operation does not effect reliable register, and slight variation of the register occurs due to the flexibility of the back of the case or inequalities on the outer edges of the case.

In accordance with the present invention the register is improved and the blocking or like operation facilitated by registering the cases by means of a guide or guides engageable with the inside edges of the boards at the back of the case.

The cases are ejected from a magazine by a pusher system having a reciprocating motion, the pushers being arranged in parallel. The side adjustment or alignment of the cases is performed by the aforesaid guide which projects above the surface on which the cases are supported by an amount approximately equal to the thickness of the boards of the cases under treatment so as to project into the space between the boards of the case.

The guide extends from the magazine to the blocking station and moves in unison with the pusher system, the arrangement being such that the cases are advanced step by step towards blocking position in the forward motion of the pusher system, the guide, in the rearward motion of the pusher system, moving differentially of the cases retrograde movement of which is prevented by stops or the like. Conveniently, the guide is constituted of separable sections detachably secured to a bar or the like connected to the pusher system. The guide is of a width equal to the distance between the inner edges of the boards of the case and in thickness is equal to the thickness of the boards minus the thickness of the cloth and back lining.

In conjunction with the aforesaid guide there are provided hold down wires movable

with the guide and located in spaced grooves cut in the upper surface of the guide, said wires being adapted to engage the back lining of the case between the boards and the back strip, the wires serving to depress the back lining into said grooves so as to ensure intimate engagement between the guide and the inner edges of the case.

The magazine, pusher system, and registering and other devices are carried by a stationary structure to which is attached a table serving as the platen of a blocking press.

A device constructed in accordance with the invention is illustrated in the accompanying drawings in which Fig. 1 is a side elevation, Fig. 2 a plan view and Fig. 3 a fragmentary section on the line 3-3 of Fig. 2. Fig. 4 is a perspective view of a book cover looking on the inside surface thereof.

The device shown includes a magazine space of which opposed side boundaries are defined between spaced vertically disposed bars 1 and of which one end boundary is defined by a pair of vertically disposed bars 1'. The magazine is adapted to be charged with a pile of book cases 2 each of which is to be subjected to a blocking operation in a blocking press indicated generally at 3, remote from the magazine. The magazine surrounds a pusher system adapted to feed the cases 2 stepwise from the magazine towards the blocking press 3 and including a pair of pusher elements 4 adapted to perform rectilinear reciprocatory movements in a horizontal plane beneath the magazine, the leading faces 5 of the pushers 4 being engageable, in a forward stroke of the pusher system, with the trailing edge of the lowermost case 2 in the magazine, whereby to eject said case from the magazine. The pushers 4 are pivoted between their ends at 6 to bolts 7 secured to members 8 mounted on transverse shafts 9, 10 carried by a pair of slides 11 engaging slideways 12 formed in the inner faces of horizontal channelled bars 13 extending longitudinally of the device and constituting the main framing thereof. Intermediate the pivots 6 and the faces 5 the pushers are pivotally connected at 14 to the upper ends of the bolts 15 vertically movable in apertures

in the members 8 whereby the pushers may be rocked on their pivots 6 so as to permit regulation of the height of the operative faces 5 thereof to suit the thickness of case being operated upon. The rear ends of the pushers engage adjustable stops constituted by set-screws 16 carried by the members 8 and adapted to be located in adjusted position by set-screws 17 opposed thereto.

5 10 Means for effecting vertical adjustment of the pushers comprises two pairs of links 18 disposed longitudinally of the device, each pair being located beneath a pusher and pivotally connected at 19 to depending lever arms 20, 21 secured to shafts 22, 23 journalled in brackets 24, 25 secured to the undersides of the bars 13. Secured to one end of the shaft 22 is a lever arm 26 to which is pivotally connected at 27 a link 28 shiftable manually to 15 20 rock the lever arms 20, 21 whereby to raise or lower the links 18. The lower end portion of each bolt 15 passes between the relative pair of links 18 and carries rollers 29 engaging the lower edges of said links, the arrangement being such that the pushers 4 are 25 constrained to participate in the rising and falling movements of the links 18 and, in the reciprocating movements of the pushers, the rollers 29 roll along the lower edges of the 30 links 18. In their reciprocation, the pushers are guided between pairs of stationary bars 30 which, in conjunction with stationary bars 31 spaced from and parallel thereto, present co-planar horizontal upper faces on which 35 rest the cases 2 during their transference from the magazine to the blocking press. Disposed intermediate the pushers 4 is a bar 32 of dovetail cross-section guided to perform reciprocatory movements in unison with the pushers 40 4, being secured at one end at 33 to the transverse shafts 9, 10. Detachably fitted to the upper face of the bar 32 are guide plates 34, 35, 36 provided with pins 37 engageable with keyhole slots 38 formed in the bar. The 45 guide plates are of a width and thickness such that their lateral edges 39 are engageable with the spaced inner edges 40 of a case 2 (Fig. 4) the cases being charged into the magazine inside face downwardly. The guide plate 34, 50 which in its reciprocatory movements passes beneath the magazine, has lateral edges 41 tapering away from the adjacent guide plate 35 so that, in a rearward stroke of the moving system, said plate engages wedgewise the 55 edges 40 of the lowermost case 2 in the magazine and brings said case into register with the guide plate. Formed in the upper faces of the guide plates 35 and 36, adjacent to the lateral edges thereof, are spaced parallel 60 grooves 42 in each of which is located a wire 43. The ends of the wires adjacent to the magazine are trained under pulleys 44 journalled on arms 45 pivoted at 46 to brackets 47 65 slidably mounted on transverse shafts 48, 49 sustained between spaced brackets 50 attached 65 by set-screws 51 to bars 52 guided for reciprocatory movements in channelled guideways 53 in the bars 13. 54 denotes pulleys which are journalled on the pivots 46 of the arms 45 and under which pass the wires 43 before being anchored to set-screws 55 carried by the brackets 47 and serving as tensioning screws for the wires 43. Pivotedly attached at 56 to the arms 45 are bolts 57 slidable in lugs 58 integral with the brackets 47. 59 denotes helical compression springs surrounding the bolts 57 and urging them and therewith the arms 45 and the pulleys 44 forwardly whereby to maintain the wires 43 in intimate engagement with the grooves 42. Pivoted to the upper ends of the bolts 57 are cams 60 provided with finger knobs 61 and engaging the upper faces of the lugs 58, said cams being operable to raise the bolts 57 and therewith the pulleys 44 and the wires 43. The 70 brackets 47 carry nuts engaging right and left-hand screw-threaded portions on a spindle 62 journalled but axially immovable in the brackets 50. By rotation of the spindle 62 in one or other direction the brackets 47 and therewith the wires 43 may be caused to approach, or to recede from one another. The opposite ends of the wires 43 are associated with anchoring means similar to that described, similar reference characters having 75 been used to indicate corresponding parts. The brackets 50 which sustain the wire anchoring means 44-62 remote from the magazine, are attached to the bars 52 at points beyond the channelled bars 13. Secured to the 80 inner faces of the bars 52 at the ends adjacent to the magazine are nut-forming lugs 63 penetrated by screws 64 revolvably mounted but axially immovable in the slides 11 and carrying worm wheels 65 meshing with worms 66 carried by a shaft 67 journalled in the slides 11. By rotation of the shaft 67 in one or other direction the slides 11 and therewith the pushers 4 may be moved to effect adjustment of the pushers to suit book cases of 85 varying sizes. The magazine bars 1 are secured to shafts 68 adjustably mounted in brackets 69 secured to the channelled bars 13, the distance between said bars being regulatable to suit different sizes of book cases. The magazine bars 1' carry racks 70 meshing with gear pinions 71 secured to a shaft 72 journalled in the brackets 6, 9, the racks 70 being slidable in vertical guides 73 carried by transverse shafts 73', 73'' also sustained by the brackets 69. Secured to one end of the shaft 72 is a toothed segment 74 meshing with a worm 75 carried by a shaft 76 journalled in the adjacent bracket 69, the arrangement being such that rotation of the shaft 76 90 in one or other direction permits regulation of the height of the bars 1' to suit different thicknesses of book cases. Pivoted at 78 to members 79 located between the stationary bars 30, 31 are two adjustable stops 80 pre- 95

senting operative faces 81 engageable, in the rearward stroke of the moving system, with the trailing edges of the book cases whereby to prevent retrograde movement of the cases. 5 The members 79 are engaged by screws 82 journalled in brackets 83 and carrying worm-wheels 84 meshing with worms 85 carried by a shaft 86 rotation of which in one or other direction permits adjustment of the longitudinal position of the stops 80. For imparting reciprocating movement to the moving system the ends 87 of links 88 pivotally attached at 89 to the transverse shaft 48 adjacent to the magazine are pivotally connected 10 to any convenient form of driving means.

In the reciprocating movements of the moving system the guide plates 35, 36 pass between the halves 90 of a table secured to the bars 13 beneath the moving head 3' of 20 the blocking press 3. Detachably secured to the upper faces of the table halves 90 are two-plates 91 to the upper surfaces of which are attached strawboard impression beds 92 the ends of which are bevelled at 93. The 25 plates 91 are attached to bars 94 provided with conical pointed set-screw 95 engageable with V-shaped grooves 96 formed in the end faces of the halves 90 of the table. The arrangement permits easy assembly and 30 disassembly of the plates with provision for easy lateral adjustment of the plates. 97 denotes the impression stamp attached to the moving head 3' of the blocking press. 98 denotes a guide carried by the head 3' and 35 adjustable by rotation of screws 99. 100 denotes stops carried by a shaft 101 journalled in brackets 102 secured to the bars 13. An arm 103 carried by the shaft 101 is spring-urged in the direction to maintain the stops 40 100 in substantially vertical position, in which position the upper ends of the stops project above the level of the impression beds 92. 104 denotes a pair of arms pivoted to a rod 105 carried by a second pair of arms 45 106 sustained by the bars 1'. The forward terminal ends 107 of the arms 104 constitute stops engageable with the trailing edges of the book cases.

In operation, in the initial rearward 50 stroke of the moving system the guide plate 34 passes beneath the magazine whereby the tapering lateral edges 41 thereof engage wedgewise the edges 40 of the lowermost book case 2 in the magazine so that said case 55 is brought into accurate register with the guide plates. In the subsequent forward stroke of the moving system the leading faces 5 of the pushers 4 engage the trailing edge of said case and eject it from the magazine, 60 the case being moved from the position shown in chain-dotted lines at A in which it is in register with the magazine to the position shown in chain-dotted lines at B in which the operative faces 81 of the stops 80 65 are located in close proximity to the trailing

edge of the case. In the second rearward stroke of the movable system retrograde movement of the case is prevented by the stops 80 and the guide plates and wires 43 slide differentially of the case. At the finish 70 of said stroke the edges 40 of the case are in engagement with the lateral edges 39 of the guide plate 35 and the case is nipped between said plate 35 and the wires 43, said wires engaging the exterior of the fabric covering of the case along the channels 108 intermediate the board covers 109 and board back strip 110. The fabric in the channels 108 is thus depressed by the wires 43 into the grooves 42 in the guide plate 35, the 80 arrangement thus ensuring intimate engagement between the edges 40 of the case and the lateral edges 39 of the guide plate 35, the case being frictionally attached to said plate. In the second forward stroke of the 85 moving system the case is carried from B to the position indicated in chain-dotted lines at C in which the board covers 109 are located on the impression beds 92 of the blocking press. The case is moved towards blocking 90 position when the moving head 3' is rising, the impression stamp 97 being, at this stage, slightly clear of the impression beds 92. The case advances until its leading edge is engaged by the stops 98 on the moving head at which point the case is located in blocking position and slight continued forward movement only of the moving system takes place. The moving head 31 now descends and effects the impression after which 95 the moving system commences its third rearward stroke. During this stroke displacement of the case from blocking position is prevented by the arms 104 the forward terminal ends 107 of which engage the trailing edge of the case. In the third forward stroke of the moving system the case is carried forwardly of the blocking press, the stops 100 being rocked by the case clear of its path. 100 As soon as the case has passed beyond the stops 100 the latter, being spring-urged, return to normal position and, when the moving system commences its fourth rearward stroke, the stops engage the trailing edge 105 of the case and eject it from the moving system, where it drops into a receptacle positioned beyond the blocking press. The position of the case at the moment of its ejection from the moving system is indicated in chain-dotted lines at D. 110

115 Although the progressive stages in the transfer from the magazine to the point of ejection from the moving system have been described for a single case only, it will be understood that each forward stroke of the moving system ejects a case from the magazine, the cases being fed step by step towards the blocking press.

I claim:—

1. A device for automatically feeding book 130

cases or covers to a blocking press, comprising a magazine, a reciprocatory pusher system adapted to eject said cases one at a time from said magazine and to feed them 5 step by step towards blocking position, normally stationary stops engageable with the cases for preventing retrograde movement thereof, and guiding means movable with said pusher system and engageable with the 10 inside edges of the boards at the back of the cases.

2. A device for automatically feeding book cases or covers to a blocking press, comprising a reciprocatory pusher system, stationary 15 stops engageable with the cases, guiding means movable with the pusher system and engageable with the cases, and a stretched wire engaging and movable with said guiding means for frictionally holding the cases to 20 said guiding means.

3. A device for automatically feeding book cases or covers to a blocking press, comprising a reciprocatory pusher system, normally stationary stops engageable with the cases, 25 guiding means movable with the pusher system and engageable with the inside edges of the boards at the back of the cases, and stretched wires engaging and movable with said guiding means for frictionally holding 30 the cases to said guiding means.

4. A device for automatically feeding book cases or covers to a blocking press, comprising a reciprocatory pusher system, normally stationary stops engageable with the cases, 5 guides movable with said pusher system and engageable with the inside edges of the boards at the back of the cases, said guides formed with grooves, stretched wires movable with said guides and serving frictionally 10 to hold the cases in engagement with said guides, said wires engaging said grooves and being adapted to grip the cases so as to depress the back linings of the cases into said 15 grooves.

45 In testimony whereof I have signed my name to this specification.

JOHN MURRAY.
